VACUUM PRODUCING EQUIPMENT

Harold M. Graham, Buffalo, N. Y., assignor, by
mesne assignments, to Ross Heater & Mfg.
Co. Inc., Buffalo, N. Y., a corporation of New
York (1933)

Application April 1, 1933. Serial No. 663,958

13 Claims. (Cl. 230—103)

This invention relates to vacuum producing equipment of the kind which utilizes steam ejectors to maintain the required vacuum in the working chamber of the apparatus with which the equipment is associated. The invention is characterized by features which render it of particular utility in connection with refrigerating systems, air conditioning apparatus, water cooling and similar systems. It is understood, of course, that the advantages of the invention may be obtained in connection with other types of apparatus, the uses specifically noted being by way of example only.

It is the practice, in connection with the use of equipment of the type generally described, to employ condensers for condensing the steam discharged from the ejectors, a vacuum of as high a degree as practical being maintained in the condensers. The degree of vacuum that can be maintained in the working chamber of the apparatus is dependent, among other factors, upon the degree of vacuum that is maintained in the condensers. As the cooling water which is circulated through the condensers is, in most cases, subject to seasonal changes in temperature, there will be corresponding variations in the vacuum in the condensers and hence, other factors remaining constant, corresponding variations in the vacuum in the working chamber. Likewise the load upon the equipment, as represented by the work to be performed in the working chamber, for example, the maintenance of a refrigerating medium at a predetermined temperature, is variable. While, therefore, the equipment must be capable of performing the work required under the most adverse conditions, such conditions are not representative of a normal load.

One object of the present invention is to provide equipment having a variable capacity, this object contemplating the use of a plurality of ejectors which may be rendered operative and inoperative as prevailing conditions require.

A further object is a novel arrangement of the ejectors and steam condensing means, whereby to provide equipment which is low in cost and which is economical from an operating standpoint.

The invention is illustrated in the accompanying drawing, in which:—

Figure 1 is a plan view of equipment embodying features of the invention.

Figure 2 is a longitudinal section taken along line 2—2 of Figure 1.

Figure 3 is a fragmentary view in elevation of a modified form of the equipment.

The invention is illustrated in connection with the cooling of a refrigerating medium which is to be circulated through the cooling coils of a refrigerating system. The system is sufficiently indicated by a showing of a chamber 5 thereof in which cooling of the refrigerating medium is effected, the said chamber being delimited by the walls of a container 5a. The refrigerating medium is conducted to the cooling chamber by a pipe 6 and is preferably introduced in the form of a spray, a predetermined quantity of the said medium being maintained in the chamber in any suitable manner. The refrigerating medium is withdrawn from the cooling chamber through a pipe 7 by a pump 8, the latter being available to effect circulation of the refrigerating medium through the cooling coils of the system.

A relatively high vacuum, for example an absolute pressure of .15 pounds, is maintained in the chamber 5 whereby the refrigerating medium which is introduced into the chamber is lowered to and maintained at the temperature required. The vacuum is produced and maintained by ejectors 9 and 10, each of the ejectors including nozzles 11. Steam is supplied to the ejectors 9 and 10 from pipes 12 and 13 respectively, each of the said pipes including a control valve 14. The ejectors are arranged in a header 15. The latter is suitably secured to a flange 16a which is formed or provided upon the container 5a and which delimits an outlet opening 16b formed therein. The steam which is discharged from the ejectors and the entrained vapors from the cooling chamber are discharged through the throats 16 and 17 of the ejectors into a condenser 18, the latter including conduits 19 and 20 with which the throats of the ejectors communicate.

The condenser 18 is divided by a partition 21 into chambers 22 and 23, the ejector 9 discharging through the conduit 19 into the former and the ejector 10 discharging through the conduit 20 into the latter. A relatively high vacuum is maintained in each of the said chambers. To this end ejectors 24 and 25 are employed. The former communicates with the chamber 22 through an intake pipe 26 while the latter communicates with the chamber 23 through an intake pipe 27. The intake pipes 26 and 27 include valves 28 and 29 respectively, whereby communication between the condensing chambers and their respective ejectors may be cut-off or established at will. Baffles 26a and 27a are prefer-

ably arranged in the chambers 22 and 23, the said baffles being adapted to deflect the incoming steam away from the entrances to the intake pipes 26 and 27. Each of the ejectors 24 and 25 includes a steam supply pipe 30 which is provided with a control valve 31 and they discharge into a common condenser 32 in which a vacuum is maintained by an ejector 33. The ejector 33 includes an intake pipe 34 which communicates with the said condenser and a throat 35 through which the steam from the ejector is discharged into a secondary condenser 36, the said secondary condenser being in communication with the atmosphere through a vent 37. The condensers 32 and 36 may be of any conventional construction and may include suitable inlet and outlet connections 32a and 36a through which cooling water may be introduced and discharged.

The condenser 18 includes heads 38 and 39. The former is divided by a partition 40 into an inlet and outlet chamber, the cooling water being introduced into the inlet chamber through a pipe 41. From the inlet chamber the water passes through the cooling tubes 41a in the chamber 22 to the head 39. The cooling water returns from the latter through the cooling tubes 42 of the chamber 23 to the outlet chamber of the head 38. The water is discharged from the outlet chamber through a pipe 43. As the cooling water is first introduced into the cooling tubes in the chamber 22 it will be apparent that the tubes in this chamber will be cooler than those in the chamber 23 through which the cooling water finally passes. The vacuum, therefore, which is maintained in the chamber 22 will be higher than that which is maintained in the chamber 23. For example, if the absolute pressure in the former is one pound then the absolute pressure in the latter will be in the neighborhood of 1.25 pounds.

Means is provided for withdrawing the condensate from the chambers of the condenser 18. To this end the said condenser is provided with a drain pipe 44 which communicates with the chamber 22. The chamber 23 is in communication with the drain pipe 44 through a conduit 46, the latter being formed or provided with a U-shaped section or trap 47 through which the condensate must flow in its passage to the drain pipe.

In the operation of the equipment, assuming that both ejectors are operating and that the absolute pressure in the chamber 5 is .15 pounds, the absolute pressure in the condensing chamber 22 one pound and that in the condensing chamber 23 1.25 pounds, then the condensate from the chamber 23 will accumulate in and flow through the trap 47 into the drain pipe 44. In the latter it accumulates with the condensate which is withdrawn from the chamber 22. The condensate which thus accumulates in the drain pipe 44 is withdrawn by a pump 48 and conducted to a convenient point of disposal.

The equipment illustrated includes two ejectors. It is to be understood that this is for the purpose of illustration only as the number of the ejectors may be varied to meet the requirements of the particular installation, such number being determined in accordance with the maximum load that the equipment is required to carry. The invention, therefore, contemplates that under normal operating conditions certain of the ejectors will not be required and hence, to the ends of economy, will be inoperative at such times. Thus, for example, in the embodiment illustrated, if it is as-

sumed that the ejector 9 is capable of carrying the normal load, then the ejector 10 will be availed of in conjunction with the former only at infrequent intervals. Thus, under normal operating conditions the control valve 14 of the ejector 10 will be closed. The ejector 9 in maintaining the required vacuum in the chamber 5 will maintain a vacuum of like degree in the throat 17 of the ejector 10, the conduit 20 and the condensing chamber 23. The vacuum, therefore, which is maintained in the chamber 23, being of substantially the same value as that maintained in the chamber 5, is higher than the vacuum which is maintained in the chamber 22, for example the absolute pressure in the chamber 23 may be one-half pound while that in the chamber 22 is one pound. In order to prevent a back-flow through the drain pipe 44 and conduit 46 to the chamber 23, and hence to the chamber 5, the legs of the trap 47 are so formed that the differential in pressures between the chambers 22 and 23 will not be high enough to force the liquid which provides the seal out of the trap. When the ejector 10 is inoperative the valve 31 of the ejector 25 may be closed. The valve 29 of the intake pipe 27 is likewise closed in order to prevent a back-flow from the condenser 32 to the condensing chamber 23. Each of the ejectors 9 and 10 may, as illustrated, be rendered operative or inoperative at will and they may be of similar or different capacities.

From the foregoing it will be apparent that the capacity of the equipment may be varied as prevailing conditions require, whereby to maintain the consumption of steam and hence the cost of operation at a minimum. A further advantage obtained is that the equipment is economical from a manufacturing standpoint.

In the embodiment shown in Figure 3, the main condenser 49 is divided, as in the embodiment described heretofore, into two condensing chambers. The said chambers which are indicated at 50 and 51, are maintained under a vacuum by ejectors 52 and 53 as has been described in connection with the embodiment shown in Figure 1. In the present embodiment each of the condensing chambers includes a drain pipe 54 through which the condensate from the condensing chambers is discharged into a collecting receptacle 55, the said drain pipes being formed to provide traps 56. The receptacle 55 is in communication with the condensing chamber 50 through a pipe 57, whereby it is maintained under a vacuum which corresponds to the vacuum which is maintained in the condensing chamber. The traps 56 permit the condensate from the condensing chambers to flow to the collecting receptacle but are adapted to prevent any back-flow between the collecting receptacle and the said chambers. The condensate which accumulates in the receptacle 55 may be withdrawn by a pump 58. In other respects the construction shown is substantially similar to that described in connection with the embodiment illustrated in Figures 1 and 2.

I claim as my invention:

1. Vacuum producing equipment including a working chamber, a plurality of ejectors which communicate with said chamber and which are adapted to maintain a vacuum therein, means for condensing the steam which is discharged from said ejectors, said means including a condensing chamber and an auxiliary ejector for maintaining a vacuum in said chamber, and means for individually rendering said first mentioned ejectors operative and inoperative at will,

whereby the capacity of the equipment may be regulated as prevailing conditions require.

2. Vacuum producing equipment including a working chamber, a plurality of ejectors which are adapted to maintain a vacuum therein, a condenser into which said ejectors discharge, means for maintaining a vacuum in said condenser and means for individually rendering said ejectors operative and inoperative at will, whereby the capacity of the equipment may be regulated as prevailing conditions require.

3. Vacuum producing equipment including a working chamber, a plurality of primary ejectors for maintaining a vacuum in the said chamber, means for individually rendering said ejectors operative and inoperative at will, a primary condenser, means for dividing said condenser into a plurality of condensing chambers, auxiliary ejectors for maintaining a vacuum in said condensing chambers, said auxiliary ejectors including intake pipes which communicate with said condensing chambers, an auxiliary condenser into which said auxiliary ejectors discharge, means for rendering said auxiliary ejectors inoperative and valves in said intake pipes, whereby in the event that one of said primary ejectors is rendered inoperative, the auxiliary ejector which is utilized in connection with the condensing chamber into which said primary ejector discharges may be rendered inoperative without permitting a back flow from the auxiliary condenser to the primary condenser.

4. Vacuum producing equipment including a working chamber, a plurality of primary ejectors for maintaining a vacuum in the said chamber, means for individually rendering said ejectors operative and inoperative at will, a primary condenser, means for dividing said condenser into a plurality of condensing chambers, said ejectors being adapted to discharge into said condensing chambers, auxiliary ejectors for maintaining a vacuum in said condensing chambers, said auxiliary ejectors including intake pipes which communicate with said condensing chambers, an auxiliary condenser into which said auxiliary ejectors discharge, means for maintaining a vacuum in said auxiliary condenser and valves in the said intake pipes, whereby in the event that one of said primary ejectors is rendered inoperative, the auxiliary ejector which is employed in connection with the condensing chamber into which said primary ejector discharges may be rendered inoperative without permitting a back-flow from the auxiliary condenser to the primary condenser.

5. Vacuum producing equipment including a working chamber, a plurality of primary ejectors which communicate with said chamber and which are adapted to maintain a vacuum therein, means for individually rendering said ejectors operative and inoperative at will, a condenser, means for dividing said condenser into a plurality of condensing chambers, one of said primary ejectors discharging into each of said condensing chambers, auxiliary ejectors for maintaining a vacuum in said condensing chambers and means for withdrawing the condensate from said condensing chambers, said means including a conduit which communicates with two of said condensing chambers and which is formed to provide a trap in which a liquid seal is maintained, whereby to prevent a back-flow between the said condensing chambers.

6. Vacuum producing equipment including a working chamber, a plurality of ejectors which

communicate with said chamber and which are adapted to maintain a vacuum therein, means for individually rendering said ejectors operative and inoperative at will, a condenser, means for dividing said condenser into a plurality of condensing chambers, one of said ejectors discharging into each of said chambers, means for maintaining a vacuum in said chambers and means for withdrawing the condensate from said condensing chambers, said means including a receptacle into which the condensate drains directly from one of said chambers and a conduit connecting another of said condensing chambers with said receptacle, said conduit being formed to provide a trap in which a liquid seal is maintained, whereby to prevent a back-flow between the said condensing chambers.

7. Vacuum producing equipment including a working chamber, a plurality of primary ejectors which communicate with said chamber and which are adapted to maintain a vacuum therein, means for individually rendering said ejectors operative and inoperative at will, means for providing a plurality of condensing chambers, said ejectors discharging into said condensing chambers, auxiliary ejectors for maintaining a vacuum in said condensing chambers and means for withdrawing the condensate from said condensing chambers, said means including a collecting chamber in which a vacuum is maintained and a conduit for connecting one of said condensing chambers with said collecting chamber, said conduit being formed to provide a trap in which a liquid seal is maintained, whereby to prevent a back-flow between said collecting chamber and said condensing chamber.

8. Vacuum producing equipment including a working chamber, a plurality of primary ejectors which communicate with said chamber and which are adapted to maintain a vacuum therein, means for individually rendering said ejectors operative and inoperative at will, means for providing a plurality of condensing chambers, said ejectors discharging into said condensing chambers, auxiliary ejectors for maintaining a vacuum in said condensing chambers and means for withdrawing the condensate from said condensing chambers, said means including a collecting chamber in which a vacuum is maintained and a conduit for connecting each condensing chamber with said collecting chamber, said conduits being formed to provide traps in which liquid seals are maintained, whereby to prevent a back-flow between said collecting chamber and said condensing chambers.

9. Vacuum producing equipment including a working chamber, a plurality of primary ejectors which communicate with said chamber and which are adapted to maintain a vacuum therein, means for individually rendering said ejectors operative and inoperative at will, a condenser, means for dividing said condenser into a plurality of condensing chambers, said ejectors discharging into said chambers, auxiliary ejectors for maintaining a vacuum in said condensing chambers and means for withdrawing the condensate from said condensing chambers, said last named means including a collecting chamber in which a vacuum is maintained and a conduit for connecting one of said condensing chambers to said collecting chamber, said conduit being formed to provide a trap in which a liquid seal is maintained, whereby to prevent a back-flow between said collecting chamber and said condensing chamber.
